UNITED STATES PATENT OFFICE

2,543,730

SELF-TRIGGERING THYRATRON PULSE
GENERATOR

Thomas F. C. Muchmore, Silver Spring, Md., assignor to the United States of America as represented by the Secretary of the Navy

Application December 30, 1948, Serial No. 68,266

1 Claim. (Cl. 250—36)

1

The present invention relates to a self-triggering thyratron pulse generator. More specifically, it relates to producing electrical pulses, that may be of extremely short duration, for example, considerably less than a microsecond, by means of a thyratron circuit that requires no separate or external triggering source for its operation.

While it is not broadly new to produce electrical pulses by means of a thyratron, heretofore it has been customary to employ, in addition to the thyratron and its immediate circuits, other separate devices for providing suitable triggering pulses to the said circuit, to cause the thyratron to fire at the desired times. Such auxiliary devices usually included electronic tubes and led to complicated apparatus and circuits.

An object of the invention is to provide a circuit, including a thyratron, that is entirely self-contained and automatic in its operation, for producing short pulses separated by relatively long and uniform intervals of inactivity, which pulses if desired may be of relatively high intensity and very short duration, of the order of one microsecond or less.

Other objects and many of the attendant advantages of this invention will be appreciated readily as the same becomes understood by reference to the following detailed description, when considered in connection with the accompanying drawings, wherein:

Fig. 1 is a diagram of a circuit that may be used in practising the invention; and

Fig. 2 is a graph illustrating the general nature of the pulses produced by the said circuit.

Referring first to the circuit, it will be seen that it is based on a four-element thyratron, that is, a gas-filled thermionic tube 1 of the tetrode type, having the envelope 2, containing a suitable gas, at low pressure, enveloping the cathode 3, control grid 4, shield grid 5 and anode 6. While conventionally a separate battery-energized heater 1 for the cathode 3 is illustrated, it is obvious that alternating current may serve equally well, and also that a directly-heated filamentary cathode may be substituted, if preferred for any reason, although in the latter case isolating inductances may be necessary. It will also be understood that while entirely independent sources 12, 18 and 24 are illustrated, in practice certain of these may be combined into a single source.

The shield grid 5 is maintained at a negative bias of 6 volts, by the conductor 11 connected to the negative terminal of a source 12 of electricity,

the positive terminal thereof being grounded by conductor 13. A relatively large-capacitance bypass capacitor 14, shown as 1000 μ uf., is connected across the source 12. This capacitance, however, is non-critical, provided only that it is sufficiently large to serve as a pulse by-pass.

The anode 6 is connected, through conductors 15 and 16 and resistor 17, to the positive terminal of a source 18 of electricity, the negative terminal thereof being grounded by conductor 19. This source 18, which need not be a battery, suitably may provide about 180 volts, and the anode resistor 17 may be of the order of 270,000 ohms.

A timing capacitor 8, which here has a value of 100 μ uf., is connected between the control grid 4 and the cathode 3 by means of conductors 9 and 10. In the circuit chosen arbitrarily for illustration, the thyratron is shown as of type 2D21.

Connected to conductors 16 and 10 is a resistor 20, the timing resistor, shown as 5 megohms, which, with capacitor 8, provides an "R. C." circuit. This resistor is thus connected between the control grid 4 and the positive terminal of the source 18. It will also be seen that the capacitor 8 may charge from the source 18 through resistor 20 and the cathode resistor 21, the latter being connected between conductor 9 leading to the cathode 3, and the grounded conductor 22.

A storage device, here shown as a "delay line" 23, of 1250 ohms characteristic impedance, is connected at one end to the conductor 15 leading to the anode 6. The resistor 21 is likewise made to have a resistance of 1250 ohms. The delay line 23 consists of a continuous helical winding or inductance 25 sheathed within a conductor 26, shown diagrammatically as forming one plate of a capacitor, the other plate of which consists of the said helically-wound inductance 23, the whole being so proportioned that the resulting characteristic impedance is of the order of 1250 ohms. The sheath 26 consists preferably of a shield braid wherein the separate conducting strands are insulated from each other, to prevent it from acting as a closed secondary winding. Storage devices other than the delay line shown may be used, for example, a network having "lumped" capacitance and inductance, or even a mere capacitor.

It is to be noted that although definite values have been mentioned for the resistances, capacitances and other electrical constants of the entire circuit, these are merely suggestive and would of course apply only to one specific example. Obviously the circuit constants and com-

ponents may be varied within wide limits, in accordance with the needs of any particular installation.

The operation is as follows:

The present circuit is self-starting, upon application of an anode-supply voltage. However, for simplicity of explanation, let the following conditions be assumed at start: Delay line 23 charged to a potential difference of 180 volts; timing capacitor 8 uncharged; thyratron 1 non-conducting. Then, upon application of anode-supply voltage the timing capacitor 8 commences charging exponentially through resistor 20 and resistor 21 towards an ultimate value of 180 volts.

Under the specified conditions of anode potential=180 volts, shield grid bias=-6 volts, the 2D21 thyratron will fire when its control-grid potential relative to its cathode becomes +43 volts. Therefore, when the potential difference across capacitor 8 reaches this value, the thyratron fires. The further rise of voltage across capacitor 8 is arrested and the latter discharges through the thyratron at an exponential rate due to the flow of current between control-grid and cathode of the said thyratron, now in the ionized state. At the same time, the delay line 23 discharges in the conventional manner through the cathode load resistor 21, the latter matching the characteristic impedance of the delay line, thus producing the desired output pulse.

The thyratron next becomes non-conducting, since its anode-to-cathode voltage falls below the level required to maintain ionization, as a result of the discharge of the equivalent storage capacitance of the delay line. Following this, both capacitor 8 and the delay line 23 commence charging towards 180 volts. In order to insure that the said line will be fully charged preparatory to the following discharge event, it is necessary that the period between successive pulses be of the order of magnitude of several times the time constant R_aC_s , wherein R_a is the resistance of anode resistor 17 and C_s represents the equivalent storage capacitance of the delay line, computed or measured at a frequency of the order of magnitude of the pulse-repetition frequency.

In place of the simple R. C. circuit comprising the resistor 20 and capacitor 8, other timing circuits may be provided, making use of various combinations involving resistance, capacitance,

and inductance but free from vacuum tubes, and often designated as "passive" networks.

Attention is called to the fact that the charging current taken by the timing capacitor 8 is of such small magnitude as to cause negligible voltage drop across resistor 21. Furthermore, an essential advantage of the circuit herein described is that the return lead 9 of capacitor 8 is connected directly to the cathode of the thyratron instead of to ground. As a result of this, the discharge current of said capacitor, which is much larger than its charging current, does not pass through resistor 21, and thereby distort the output waveform.

Obviously many modifications and variations of the present invention are possible in the light of the above teachings. It is therefore to be understood that within the scope of the appended claim the invention may be practiced otherwise than as specifically described.

What is claimed is:

A pulse generating circuit including a gaseous tetrode, having a cathode, a control grid, a shield grid and an anode, a source of electricity for energizing said anode, a resistor connecting the positive terminal of said source to said anode, a timing capacitor having its terminals connected to the cathode and the control grid respectively, a timing resistor connecting the said control grid to the positive terminal of the source of electricity, means for negatively biasing the shield grid, a delay line comprising a continuous winding connected at one end to the anode, and a grounded sheath surrounding said winding, and a resistor of substantially the same equivalent impedance as said delay line, and connecting the cathode and ground.
